(57) **ABSTRACT**

'Gradisca' apple tree is the product of an open pollination of 'Fuji' apple, and is characterized by its bright red fruit and good production capacity. Fruit of 'Gradisca' is sweet and perfumed, and colors well in hot weather. 'Gradisca' is distinguished from its parent 'Fuji' by its more perfumed fruit and more intense red overcolor.

5 Drawing Sheets

1

Latin name: *Malus domestica* Borkh.
Variety denomination: 'Gradisca'.

BACKGROUND OF THE VARIETY

'Gradisca' is a new and distinct cultivar of apple tree *Malus domestica* Borkh discovered in an established 'Fuji' (not patented) orchard. This new cultivar originated as a seedling resulting from the open pollination of a 'Fuji' apple tree, and is characterized by its bright red fruit and good production capacity. 'Gradisca' was first observed in Mudaison, France in 1994. Asexual reproduction by budding and grafting was first carried out at Mudaison in 1996. 'Gradisca' has since been observed to remain true to type over successive asexually propagated generations.

BRIEF DESCRIPTION OF THE VARIETY

'Gradisca' was first selected for its attractive bright red fruit and for its productivity. Fruit of 'Gradisca' is sweet and perfumed, and colors well in hot weather. There is no equivalent apple with the same organoleptic qualities in the same picking period.

'Gradisca' is distinguished from its parent 'Fuji' by its more perfumed fruit and more intense red overcolor. Fruit of 'Gradisca' is similar in color to that of 'Rosy Glow' (not patented), but 'Gradisca' is easily distinguished from 'Rosy Glow' by its early harvest maturity, at least one month prior to 'Rosy Glow'.

2

BRIEF DESCRIPTION OF THE PHOTOGRAPHS

FIG. 1 shows the leaves of 'Gradisca';

FIG. 2 shows 4th-leaf trees of 'Gradisca' one week before
5 picking;

FIG. 3 shows a fruit of 'Gradisca';

FIG. 4 shows picked whole fruit of 'Gradisca'; and
FIG. 5 shows a sectioned fruit of 'Gradisca'.

DETAILED BOTANICAL DESCRIPTION OF
THE VARIETY

The following detailed botanical description is based on
15 observations made during the 2016 growing season (unless
otherwise noted) at Mudaison, France of four-year-old trees
grown on 'M9 EMLA' rootstock (not patented). All colors
are described according to The Royal Horticultural Society
Colour Chart, 5th edition, version 2. It should be understood
20 that the characteristics described will vary somewhat
depending upon cultural practices and climatic conditions,
and will vary with location and season. Quantified measure-
ments are expressed as an average of measurements taken
from a number of individual plants of the new variety. The
measurements of any individual plant or any group of plants
25 of the new variety may vary from the stated average.

Tree:

Vigor.—Vigorous.

Type.—Ramified, drooping.

Habit.—Semi-upright tree with one trunk and one
leader, main branch spreading.

Height.—3.20 m.

Spread.—2 m.

<i>Trunk diameter</i> .—5.8 cm at 30 cm above the graft union.	5	Pedicel:
<i>Bark texture</i> .—Fairly smooth with slight crevice and small lenticels.		<i>Length</i> .—16 mm to 19 mm.
<i>Bark coloration</i> .—Light brown 162A.		<i>Diameter</i> .—3 mm.
<i>Lenticels</i> .—2 mm; light beige 159D.		<i>Color</i> .—Greyed-orange N172C.
Branch (fruiting branches located at around 1 m above the graft union):		5 Sepals:
<i>Length</i> .—1.50 m.		<i>Quantity</i> .—5.
<i>Diameter</i> .—16 mm to 20 mm.	10	<i>Color</i> .—Green 135B.
<i>Crotch angle</i> .—80° to 90°.		<i>Length</i> .—8 mm to 11 mm.
<i>Color</i> .—Dark brown with grey highlights 165B.		<i>Width</i> .—2 mm to 3 mm.
<i>Lenticels</i> .—1.5 mm; beige 159D; 4 to 8 per cm ² .		<i>Shape</i> .—Triangular.
One-year-old shoot:		<i>Margin</i> .—Entire.
<i>Length</i> .—25 cm to 35 cm.	15	<i>Texture</i> .—Weakly pubescent.
<i>Color</i> .—Very light brown 160A.		Leaves:
<i>Pubescence</i> .—Strong.		<i>Shape</i> .—Ovate.
<i>Thickness</i> .—3 mm to 5 mm.		<i>Length (petiole not included)</i> .—7 cm to 9 cm.
<i>Internode length</i> .—13 mm to 22 mm.	20	<i>Width</i> .—5 cm to 6 cm.
<i>Lenticels</i> .—1 mm; white NN155A; 11 per cm ² .		<i>Length/width ratio</i> .—1.4 to 1.6.
Winter hardiness:		<i>Blade margin</i> .—Biserrate.
<i>Hardiness</i> .—Hardy in area tested (USDA hardiness zone 9A).		<i>Apex</i> .—Acuminate.
<i>Chilling requirement</i> .—Medium; between 450 hours and 650 hours.	25	<i>Base shape</i> .—Cuneate.
Flower buds:		<i>Color of top surface</i> .—Green 134A.
<i>Quantity per spur</i> .—4 to 5.		<i>Color of bottom surface</i> .—Green 140B.
<i>Shape</i> .—Globose.		<i>Texture</i> .—Upper surface — Smooth.
<i>Diameter</i> .—10 mm to 12 mm.		<i>Texture</i> .—Lower surface — Moderately pubescent.
<i>Color</i> .—Red purple 63B.		<i>Venation</i> .—Pinnate.
Flowers:		<i>Vein color</i> .—Yellow green 1B.
<i>Color (balloon stage)</i> .—Light pink 36D.		<i>Attitude in relation to shoot</i> .—Outward.
<i>Diameter of open flower</i> .—2 cm.		Petiole:
<i>Depth</i> .—0.8 cm.	30	<i>Length</i> .—18 mm.
<i>Number per cluster</i> .—4.		<i>Diameter</i> .—2 mm.
<i>Fragrance</i> .—Light.		<i>Color</i> .—Green 142A.
<i>Pollination requirement</i> .—Pollinator required.		Fruit:
Petals:		<i>Quantity per cluster</i> .—4.
<i>Quantity per flower</i> .—5.	35	<i>Diameter</i> .—70 mm to 80 mm.
<i>Shape</i> .—Ovate.		<i>Height</i> .—70 mm to 80 mm.
<i>Length</i> .—15 mm to 18 mm.		<i>Weight</i> .—200 g.
<i>Width</i> .—14 mm to 16 mm.		<i>Ratio of height to width</i> .—Nearly 1:1.
<i>Color of upper surface</i> .—White NN155D.	40	<i>General shape in profile</i> .—Globose slightly conical.
<i>Color of lower surface</i> .—White NN155D.		<i>Position of maximum diameter</i> .—At middle.
<i>Texture</i> .—Smooth.		<i>Ribbing</i> .—Absent.
<i>Margin</i> .—Entire.		<i>Crowning at calyx end</i> .—Absent or weak.
Pistils:		<i>Aperture of eye</i> .—Closed.
<i>Length</i> .—12 mm to 13 mm.	45	<i>Size of eye</i> .—8 mm.
<i>Color</i> .—Yellow-green 145C.		<i>Length of sepal</i> .—4 mm to 7 mm.
Anthers:		<i>Depth of eye basin</i> .—9 mm to 13 mm.
<i>Quantity</i> .—16.		<i>Width of eye basin</i> .—23 mm to 25 mm.
<i>Size</i> .—2 mm.		<i>Length of stalk</i> .—13 mm to 19 mm.
<i>Pollen</i> .—Present.		<i>Thickness of stalk</i> .—4 mm.
<i>Pollen color</i> .—Yellow 9B.	50	<i>Width of stalk cavity</i> .—17 mm.
Stigma:		<i>Depth of stalk cavity</i> .—13 mm.
<i>Size</i> .—1 mm.		<i>Size of lenticels</i> .—1.5 mm.
<i>Color</i> .—Yellow 11C.		<i>Bloom of skin</i> .—Absent.
Style:		<i>Greasiness of skin</i> .—Absent.
<i>Size</i> .—8 mm.	55	<i>Background colour of skin</i> .—Yellow 7A.
<i>Color</i> .—Yellow-green 145C.		<i>Over colour of skin</i> .—Red-pink N33A.
Bloom:		<i>Amount of overcolor</i> .—70% to 90%.
<i>Date of first bloom</i> .—April 10 th (Mudaison, Hérault, southern France).	60	<i>Intensity of overcolor</i> .—Very intense.
<i>Date of full bloom</i> .—April 14 th (Mudaison, Hérault, southern France).	65	<i>Pattern of overcolor</i> .—Solid flush.
		<i>Skin texture</i> .—Fine, smooth.
		<i>Flesh texture</i> .—Firm and light.
		<i>Aroma</i> .—Good eating quality, sweet and perfumed.
		<i>Juiciness</i> .—Juicy.
		<i>Brix</i> .—13.5 to 15.5.
		<i>Flesh color</i> .—Yellow 4B.
		<i>Stem color</i> .—Light pink 39D.

US PP30,008 P3

5

Locule length.—18 mm to 23 mm.

Locule width.—5 mm to 6 mm.

Number of locules per fruit.—5.

Seeds:

Quantity per fruit.—8 to 10.

Shape.—Oval.

Color.—Brown 200D.

Harvest:

Amount of fruit produced per harvest.—30 kg per tree.

Harvest date.—October 1 to October 13 (2017 growing season, Mudaison, Hérault, southern France).

6

Storage characteristics.—6 months in standard cold storage; 9 months in controlled atmosphere storage.

Market use.—Fresh.

Diseases/pests:

Resistance.—None noted.

Susceptibility.—Susceptible to scab (*Venturia inaequalis*).

We claim:

1. A new and distinct apple tree named 'Gradisca' substantially as described and illustrated herein.
